UNITED STATES PATENT OFFICE.

PATRICK H. VAUGHN, OF MORRIS, MINNESOTA.

GRAIN SEPARATOR.

Application filed March 1, 1920. Serial No. 362,366.

To all whom it may concern:

Be it known that I, PATRICK H. VAUGHN, a citizen of the United States, residing at Morris, in the county of Stevens and State 5 of Minnesota, have invented certain new and useful Improvements in Grain Separators; and I do hereby declare the following to be a full, clear, and exact description of the invention; such as will enable others 10 skilled in the art to which it appertains to make and use the same.

My invention relates to improvements in grain separators of the type disclosed and claimed in my U. S. Letters Patent 15 #1,321,263, issued November 11, 1919.

To the above end, the invention consists of the novel devices and combinations of devices hereinafter described and defined in the claims.

20 In the accompanying drawings, which illustrate the invention, like characters indicate like parts throughout the several views.

Referring to the drawings:

25 Fig. 1 is a side elevation of the improved grain separator with some parts broken away;

Fig. 2 is a view of the same in a central vertical section;

30 Fig. 3 is a fragmentary transverse section taken on the line 3—3 of Fig. 2;

Fig. 4 is a fragmentary detail view taken on the line 4—4 of Fig. 2; and

35 Fig. 5 is a fragmentary view in central vertical section illustrating a different method of operating the screening sieve and with the scalping sieve removed.

The frame of the improved grain separator includes four legs arranged in front 40 and rear pairs 6 and 7, respectively. The legs of each pair are rigidly connected at their lower ends by relatively wide transverse boards 8. The upper ends of the legs 6 and 7 are rigidly connected on each 45 side of the separator by bolting the same to the sides of a feed-hopper 9. The legs 6 and 7 are further connected on each side of the separator by a relatively narrow board 10, and a relatively wide board 11, 50 the former of which is located just under the hopper 9 and is inclined toward the rear of the separator, and the latter of which is located just above the transverse boards 8 and also inclined toward the rear of the 55 separator.

The two boards or transverse members

which constitute the bottom of the hopper 9, are spaced at their lower adjacent edges to afford a feed-opening 12, located at substantially the center of the separator. A 60 feed-roller 13, of the type disclosed and broadly claimed in my co-pending U. S. application, filed Dec. 20, 1919, under S. N. 346,326, is located at the feed-opening 12 and its shaft is journaled in bearings 14 secured to the outer faces of the sides of the hopper 9. An adjustable gate 15 is provided for regulating the flow of grain from the hopper 9.

Mounted in the frame, at the front thereof, is a fan casing 16 having a long rearwardly projecting throat 17, and which casing and throat are located between and rigidly secured to a pair of laterally spaced bars 18, the rear end portions of which are 70 pivoted at 19 to the legs 7 and the front end portions of which are rigidly and adjustably connected by nut-equipped bolts 20, which extend through slots 21 in said legs 6 to permit a slight vertical adjustment of 80 the fan casing 16. Mounted in the fan casing 16 is a fan 22, the shaft of which is journaled in bearings 23 secured to the bars 18.

Rigidly secured to the projecting right-hand end of the shaft of the feed-roller 13 is a large hand-crank-equipped sprocket wheel 24. A sprocket chain 25 is arranged to run over the sprocket wheel 24 and a relatively small sprocket wheel 26, secured to 90 the projecting right-hand end of the shaft of the fan 22. On the other end of the shaft of the fan 22, is secured a second sprocket wheel 27. Both sprockets 26 and 27 are provided with wrist pins 28, for a 95 purpose that will presently appear. Located between the hopper 9 and fan casing 16 is a shoe 29, the front end of which is suspended from the hopper by a pair of links 30. The rear end of the shoe 29 is 100 supported by the upper or short ends of a pair of vertically disposed levers 31 intermediately fulcrumed at 32 on the bars 18.

Mounted in the shoe 29 is a gang of scalping sieves 33, under which is an imperforate deck 34 secured to the shoe 29 with its 105 delivery end terminating under the receiving portion of the lowermost sieve of the gang 33. Secured in the shoe 29, at the receiving end of the uppermost sieve of the 110 gang 33, is an imperforate deck 35, which, as shown, is an independent member from

the frame of said uppermost sieve, but in some instances, might constitute the upper transverse portion of said frame. Vibratory movement is imparted to the shoe 29, 5 through the levers 31, by a pair of operating bars 36 having one of their ends secured to the wrist pins 28 and their other ends pivotally connected to the lower or long ends of said levers 31.

10 The rear end of the top plate of the fan casing throat 17 terminates substantially under the delivery end of the deck 34 and is curved slightly downward to afford a deflecting flange 37. Extending upward and 15 forward from the deflecting flange 37, is a deflecting board 38 secured to the bars 18. Secured to the casing throat 17 is a forwardly inclined deck 39 spaced apart from the flange 37 to afford therebetween a pass- 20 sageway 40 for the grain precipitated from the gang 33. Grain entering through the passageway 40 will be precipitated onto an underlying adjustable deflector 41 arranged to direct the said grain toward the front of 25 the machine. The rear end of the bottom plate of the throat 17 terminates short of the deflector 40 to afford therebetween a relatively wide grain passageway 42, and which rear end portion of the said bottom 30 plate is curved upward to afford a deflecting surface 43.

An adjustable damper 44 is mounted in the throat 17. Underlying the fan casing 16 and its throat 17, is a lower rearwardly inclined sieve 45, mounted for reciprocatory movement on cleats 46 secured to the frame boards 11. Underlying the sieve 45 and co-operating with the under face thereof, is a multiplicity of transverse cleaning slats 47, 40 which are rigidly connected by a plurality of longitudinal bars 48, which, in turn, are secured to a plurality of transverse bars 49, the ends of which are removably seated in the cleats 46. Reciprocatory movement is 45 imparted to the rear sieve 45 from the levers 31 by a rock-shaft 50 and a rod 51. The ends of the rock-shaft 50 are pivoted in the levers 31, and one end of the rod 51 is inserted through the intermediate portion of the 50 rock-shaft 50 and is adjustably secured thereto by a pair of opposing nuts 52. The other end of the rod 51 is bent laterally upward to form a pivot, which is mounted in a bore formed in the rear transverse mem- 55 ber of the frame of the lower sieve 45.

Above the shoe 29, is a downwardly and forwardly inclined upper screening sieve 53, and it is important to note that this sieve is inclined in an opposite direction from the 60 gang of sieves 33. The screening sieve 53 is mounted for reciprocatory movement that is oblique to the movement of the shoe 29 on cleats 54 secured to the boards 10. Reciprocatory movement is imparted to the 65 screening sieve 53 from the shoe 29, as

shown in Fig. 2, by means of a pair of vertically disposed levers 55 intermediately fulcrumed at 56 to the boards 10. The fulcrums 56 for the levers 55 may be longitudinally adjusted thereon by forming in 70 said levers a plurality of aligned pairs of longitudinally spaced holes. The upper ends of the levers 55 are connected to the screening sieve 53 by a rock bar 57 and a link 58. The ends of the rock bar 57 are journaled 75 in any one aligned pair of a plurality of longitudinally spaced holes in the levers 55 to permit said rock bar to be adjusted toward or from the fulcrums of the levers 55.

One end of the link 58, which, as shown, is 80 in the form of a rod, is inserted through a bore in the intermediate portion of the rock bar 57 and adjustably secured thereto by a pair of opposing nuts 59, which have screw-threaded engagement therewith, to vary the 85 operative length of said link. The other end of the link 58 is bent laterally downward to form a pivot pin 60 turnably mounted in a bore in the upper transverse member of the frame of the screening sieve 53. The lower ends of the levers 55 are pivotally connected to the sides of the shoe 59 by a pair of links 61.

The connections just described, for imparting the reciprocatory movement of the 95 screening sieve 53 from the shoe 29, are such as to move said screening sieve simultaneously with the shoe 29, but in an opposite direction. Underlying the screening sieve 53 is a multiplicity of laterally spaced trans- 100 verse cleaning bars 62 which co-operate with the under face of said sieve to keep the same clean. These cleaning bars 62 are secured to longitudinally extended bars 63, which, in turn, are secured to bars 64, the ends of 105 which are mounted in seats formed in the cleats 54 and removably support the cleaning bars 62 from the frame boards 10. Obviously, by adjusting the nuts 59, the operative length of the link 58 may be 110 changed, at will, to vary the position of the screening sieve 53 on the cleaning bars 62.

The delivery end of the screening sieve 53 terminates over the imperforate deck 35. Underlying the screening sieve 53 is a pan 115 65 carried by the shoe 29 and arranged to deliver, to the left-hand side of the separator, materials precipitated from said screening sieve. Interposed between the hopper 9 and cleaning sieve 66, is a scalping 120 sieve 66, which, as shown, is supported upon and detachably secured to the frame of said cleaning sieve. This scalping sieve 66 has its delivery end extended beyond the delivery end of the cleaning sieve 53 to support and hold a transversely inclined trough 125 67 arranged to deliver to one side of the machine.

Referring now to the construction shown in Fig. 5, the connections 55 to 61, inclusive, 130

are arranged to impart a reciprocatory movement to the screening sieve 53 that moves said screening sieve simultaneously in the same direction with the shoe 29. To 5 thus reciprocate the screening sieve 53, the levers 55, at their upper ends, are pivoted to the sides of the hopper 9 and the lower ends of said levers are pivotally connected to the sides of the shoe 29 by the links 61. 10 The links 61 may be attached to the levers 55 at different longitudinally spaced points to vary the swinging movement of said levers. The rock bar 57 is intermediately pivoted to the levers 55 with freedom for 15 adjustment longitudinally in respect thereto.

Operation.

The materials to be separated are placed in the hopper 9, as indicated at *a*, and the 20 movable parts of the machine operated by turning the hand-crank-equipped sprocket wheel 24 in a direction to cause the feed-roller 13 and fan 22 to rotate, as indicated by arrows marked on Fig. 2. Under the rotation 25 of the feed-roller 13, a constant and even feed of materials, from the hopper 9 to the screening sieve 53, is obtained. The scalping sieve 66 is provided to remove from the materials *a*, all coarse materials, such 30 as sticks, straws and the like, and deliver the same to one side of the machine through the trough 67. The reciprocatory movement of the screening sieve 53 causes the materials *a* thereon to travel downward. 35 During this travel of the materials *a* on the sieve 53, all dust and small foul seeds are released therefrom, screened through said sieve and precipitated into the pan 65 and delivered at one side of the separator, as 40 indicated at *b*.

By the use of the rake bars 62, it is possible to use a wire mesh screen for removing dust and small foul seeds from the materials *a*. By thus first separating the dust 45 and small foul seed from the materials *a*, the machine is free from dust when said materials are subjected to the air blast after passing through the scalping sieve. It also immediately relieves the machine from handling such materials as removed by the screening sieve 53. Materials *a*, tailed over the screening sieve 53, are precipitated onto the deck 35 and the direction of travel thereof reversed by the deck from the front to 55 the rear of the machine.

From the deck 35, the remaining materials *a*, to be separated, are delivered to the gang of sieves 33, and the streams of grain passing downward through said gang 60 are indicated at *c*. All coarse material, not removed by the scalping sieve 66 from the small seed grains, such as wheat, barley, rye, flax, etc., will be deposited at the rear of the machine by the gang of sieves 33, as 65 indicated at *d*. The streams of grain *c*,

from the gang of sieves 33, are deposited on the deflecting board 38 and deck 39, from whence they will be delivered through the passageway 40, with the assistance of the deflector 37, and precipitated onto the adjustable deflector 41. At this time, the grain *c* is subjected to the under-shot blast of air from the fan 22, which removes therefrom all materials not desirable for seed. Of course, by regulating the damper 44, the amount of such materials removed from the grain may be varied, at will. From the deflector 41, the grain *c* is precipitated directly onto the sieve 45, which again changes the direction of travel of said grain from the rear to the front of the machine and removes the oats therefrom, as indicated at *e*.

By independently mounting the screening sieve 53 in respect to the shoe 29, a very smooth reciprocatory movement is imparted thereto, which is highly desirable in the separation of grass seed, clover seed, and the like. As previously stated, the connections shown in Fig. 2 impart a simultaneous reverse movement to the screening sieve 53 in respect to the shoe 29 and, by shifting the fulcrums 56 on the levers 55, the throw of said sieve may be varied, at will, or the rock bar 57 may be longitudinally adjusted on the levers 55 to vary the throw of the sieve 53. In the arrangement of the operating connections for the screening sieve 53 in Fig. 5, the throw of said sieve may be varied in respect to the shoe 29 either by raising or lowering the connection of the links 61 with the levers 55, or raising or lowering the rock bar 57 on said levers, or both of said adjustments may be made.

What I claim is:—

1. A grain separator comprising a frame, a feed hopper mounted at the top thereof, an inclined scalping sieve slidably mounted beneath the hopper and receiving therefrom a fine screening sieve slidably mounted beneath said scalping sieve, a stationary cleaning device disposed beneath said fine sieve and closely adjacent thereto, a swinging sieve-equipped shoe to which said fine sieve delivers mounted below the same and a laterally delivering pan carried by said shoe and extending beneath said fine screening sieve. 105

2. A grain separator having in combination, a frame, a feed hopper at the top thereof, an inclined scalping and a fine screening sieve superposed and slidably mounted as a unit beneath said hopper, a laterally discharging trough carried by said scalping sieve, a removable cleaning device carried by said frame beneath said fine screening sieve, a swinging sieve-equipped shoe mounted below said sieves and inclined oppositely thereto onto which the fine sieve discharges, and a laterally discharging pan carried by said shoe extending beneath said fine screening sieve. 110

3. A grain cleaner having in combination, a frame, a hopper at the top thereof, a scalping and fine cleaning sieve slidably mounted below the hopper, a cleaning device beneath the latter and in substantial contact therewith, a swinging sieve-equipped shoe mounted beneath said sieves and carrying a pan having a laterally discharge spout, said pan extending beneath said fine screening sieve;
5. the latter and in substantial contact therewith, a swinging sieve-equipped shoe mounted beneath said sieves and carrying a pan having a laterally discharge spout, said pan extending beneath said fine screening sieve;
10. an open sided chute into which the screened material from said shoe discharges, means for passing a blast of air through said chute, a slidably mounted screen onto which said chute delivers, and a cleaning device in contact with the bottom of said latter screen.
15. 4. A wheat cleaner having in combination, a frame, a hopper disposed at the top thereof, a scalping sieve and a fine screening sieve slidably mounted adjacent said hopper for removing the coarse and fine refuse respec-

tively, depending links at one side of said frame, vertically extending levers at the other side of said frame below said links, a sieve-equipped shoe hung at one end on said links and carried at its other end by the top of said lever for removing foul and foreign seeds, a sliding sieve below said shoe connected to said levers between their pivot joints and the lower ends thereof for removing oats from the wheat, a driving shaft, 30 and a crank operated pitman connected to the lower end of said levers to reciprocate said shoe and last mentioned sieve and driven by said shaft.

In testimony whereof I affix my signature 35 in presence of two witnesses.

PATRICK H. VAUGHN.
